MIXER TRAILER

Bert Orland Underwood, Oklahoma City, Okla., assignor to The Boardman Co., Oklahoma City, Okla., a corporation of Oklahoma

Application May 11, 1955, Serial No. 35,941

Term of patent 14 years

(Cl. D14—3)

Fig. 1

Figure 1 is a perspective view of one side of a mixer trailer showing my new design, the vertical conveyor being illustrated in its inoperative position.

Figure 3 is a perspective view looking at the rear end of the mixer trailer, the conveyor being illustrated in its vertical position.

I claim:

The ornamental design for a mixer trailer, as shown.
